Primary Examiner — David Muller*Assistant Examiner* — Nathan Johnston(74) *Attorney, Agent, or Firm* — Erickson Kernell Derousseau & Kleypas, LLC(57) **CLAIM**

The ornamental design for a cleaning and massaging device, as shown and described.

DESCRIPTION

FIG. 1 is a side elevation view of an ornamental design for a cleaning and massaging device;

FIG. 2 is a front elevation view thereof;

FIG. 3 is a back elevation view thereof; and,

FIG. 4 is a front perspective view thereof.

The broken lines in the figures form no part of the claimed design.
